COMBUSTION ENGINE

William Harper, Jr., Port Washington, N. Y., assignor to H. B. Motor Corporation, a corporation of New York

Application March 27, 1933, Serial No. 662,893

23 Claims. (Cl. 123—148)

This invention relates to combustion engines and is a continuation in part of my applications Serial No. 509,947, filed January 20, 1931, and Serial No. 646,224, filed December 8, 1932.

5 The object of this invention is to provide an improved ignition system and method whereby to increase the power output and general overall efficiency of combustion engines, and particularly high speed, high compression engines wherein 10 such high temperatures are developed as to produce troubles both from fouling of the spark plugs and impairment of the designed spark plug insulation.

Ordinary spark plugs retain their designed insulation and capacity for conducting away the heat without fusing the porcelain or other insulation up to and beyond moderate high speeds. When very high speeds are used, as is the tendency in modern combustion engine development, 20 the period between explosions is so short that ordinary plugs readily become overheated, and thereby tend to lose their insulation and may even fuse, as well as crack the fuel and foul by the deposited carbon. To meet this condition plugs are 25 obtainable on the market which have a good heat conducting capacity, but at the expense of high insulating quality, and also plugs have been developed having a very high insulating quality but at the expense of heat conducting capacity.

30 A peculiar phenomenon occurs in the normal operation of common insulated spark plugs, to wit: It is an established fact that porcelain, mica and other porous insulating materials have a pronounced catalytic action in the decomposition of 35 hydrocarbons at various temperatures. In the presence of such porous materials radiant heat will break down free carbon first, and combined carbon secondly, into component gases, the ultimate being CO_2 and water vapor. The critical 40 temperature at which this phenomenon occurs in the presence of the catalyst is approximately 750° F. Hence if any part of the spark plug attains a temperature of 750° F. the radiant heat thrown off will start this reaction which is accumulative 45 in the temperature range.

It also happens that the above decomposition gases such as carbon dioxide, and to a lesser extent carbon monoxide, are very good conductors 50 of high tension current especially when they are intensified by high compression. Therefore as any point of the spark plug reaches or exceeds the above critical temperature, gases developed in the proximity of the spark gap will progressively bleed the potential of the discharge until the discharge

of the hot spark will disappear completely and the plug will be shorted by a gas pocket.

In operating an engine under these conditions the performance is deceptive as to the real cause of incomplete combustion. As the engine begins 5 to miss the indications are that the mixture is too lean as an examination of the spark plugs will show that they are perfectly clean and functioning properly. The natural thing to do is to enrich the mixture which thus prevents the missing 10 and allows the motor to increase its power output. However, if an examination is made of the analysis of exhaust gases from an engine operated under these conditions a large percentage of CO running anywhere from 1% to 7% will be in evidence in the exhaust. This is unnatural in that as the temperature and speed of an engine are increased the thermal efficiency of the fuel should also increase.

There are thus two conditions under which a 20 spark plug will fail to function as an igniting point for compressed gas. One is when the plug is too cold and causes short-circuiting on the surfaces of its insulation due to the deposit of 25 condensed carbonaceous matter acting as a conductor of high tension current. The other condition is the other extreme, at which the plug becomes too hot, although perfectly clean, and spontaneously with its temperature develops an invisible gas conductor which short-circuits the 30 high tension current in the gap of the plug without developing sufficient heat energy to bring about ignition.

Difficulties due to inefficient spark plug ignition resulting in excessive fuel consumption are 35 quite noticeable in automobiles which follow the modern trend of higher motor speeds and higher compression ratios to obtain higher efficiency. Theoretically, increased motor speeds and compression ratios should result in increased efficiency but in practice this is not the case, one particular eight-cylinder car in the low price field using as much fuel as a much larger and heavier automobile. Another somewhat larger car uses dual ignition, or two spark plugs in each cylinder, 45 in order to obtain more rapid flame propagation and partially compensate for the loss of efficiency due to higher compression and temperature at the spark plugs. After considerable study and discussion with various carburetor experts it is 50 my belief that the carburetor has been thoroughly perfected and that the deficiency lies in the ignition for reasons stated above.

55 My invention provides a dual ignition system for combustion engines which largely overcomes

the above difficulties with little or no change in the cylinder head construction of cars and motors now on the market. It employs a plurality of spark plugs in constant or permanent communication with the combustion space, having individual electrical ignition characteristics which vary over the range of temperatures developed in the combustion space and a combined electrical ignition characteristic which under all conditions is at least equal to the maximum ignition efficiency of either plug alone.

While the invention is not limited to two spark plugs in each combustion space I have found two plugs sufficient in all my experiments. One of these plugs is of the high insulation, less heat conducting type or what I call the low temperature or priming plug, having maximum electrical ignition efficiency at the relatively low temperatures developed in the combustion space when the engine is started and operated at low speeds. The other plug is what is commonly known as a cold plug, having rapid heat dissipating properties and hence maximum electrical ignition efficiency at the relatively high temperatures developed in the combustion space when the engine is operated at high speeds.

Under starting conditions and idling and low speeds the priming plug functions in the usual way, having sufficient insulating surface to prevent fouling. As the temperature increases the electrical ignition efficiency of this plug will diminish due to the presence of the short-circuiting element of gas generated in the zone of the spark gap, until it may have but 25% or less of its original potential in the center of hotness of its spark. While this condition is being approached, the increasing temperature will have cleaned the cold plug of any surface condensation which may have caused leakage and short-circuiting of the high tension current, and when this deposit is burned off the cold plug, which is connected in circuit so as to be energized simultaneously with the priming plug, will function as the main ignition point at 100% of its electrical efficiency.

When an engine equipped with my ignition system is run at high speeds the electrical ignition efficiency of the cold plug is 100% and that of the priming plug may be around 25%, making a total electrical ignition efficiency of approximately 125% as compared with the maximum efficiency of the cold plug alone, whereas the combined efficiency of two priming plugs would under the same conditions be but 50%. Of course, it would be desirable to combine the ignition characteristics of two cold plugs but because of the rapid heat dissipating properties of such plugs they would foul and be ineffective under starting conditions or continued idling, and therefore unreliable when used alone.

There are certain situations in which it is desirable, and others in which it is essential, to shield the priming plug to protect it against excessive radiant heat. For example, in a two-cycle engine twice as much heat will be developed in a given time than in an equal time and number of revolutions by a four-cycle engine. In most two-cycle engines I therefore prefer to shield the priming plug in a recess having a restricted passage leading into the combustion space as disclosed in my above applications or as hereinafter described. Furthermore, my said applications disclose a two-cycle engine which is capable of very high speed, developing temperatures considerably in excess of 2000° F., and under such conditions it is essential to shield the priming plug to prevent

breaking down of the spark plug insulation and possible fusing of the porcelain body. As the design of four-cycle engines is improved so as to obtain higher speeds it becomes increasingly desirable to shield the priming plug against the radiant heat.

There are also situations in which it is desirable or essential to shield the priming plug for reasons other than protection against radiant heat. The chief of these reasons is that the modern trend is to use alcohol and other fuels which are less inflammable and less volatile than the common gasoline, especially for such engines as are installed in boats and aircraft. In using such fuels it is difficult to attain gasification sufficient to bring about ignition from an ordinary spark plug. If sufficient heat is put into the mixture at the carburetor this heat is largely dissipated in travel through manifolds, etc., before it reaches the spark plug, and excessive condensation results during the compression stroke. By shielding the priming plug in a recess having a restricted communication with the compression chamber, as this so-called safety fuel is compressed by the piston, mechanical heat from friction or wire drawing is put into a small percentage of the mixture as it is pushed by the compression of the piston into the recess containing the priming plug. The point of ignition of this plug is in close proximity to the restricted passage and a large percentage of the heat is available for gasifying a portion of the mixture in the zone of the spark gap where it will be ignited before such heat has been dissipated to any large extent; therefore the principle of developing heat in a portion of the gas charge right at the point of ignition by the mechanical action of the engine is beneficial in the use of less inflammable fuel. My invention provides a self-shielding spark plug which may be used in existing engines with little or no change in the cylinder head construction.

I shall describe my invention in connection with the accompanying drawings wherein:

Fig. 1 is a vertical section through a four-cycle engine embodying the invention;

Fig. 2 is a diagrammatic view of the ignition system showing the detailed construction of the spark plugs;

Fig. 3 is a diagram illustrating the operating characteristics of the spark plugs;

Fig. 4 is a diagrammatic view of an ignition system using other spark plugs;

Fig. 5 is a vertical section through a two-cycle engine having a shielded priming plug; and

Fig. 6 is a diagrammatic view of the ignition system of Fig. 5.

The four-cycle engine shown in Fig. 1 is of any suitable construction, having a cylinder 1 with a water-jacketed wall 2, explosion driven member or piston 3, inlet valve 4 and exhaust valve 5. Spark plugs 6 and 7 are set in recesses 8 and 9, respectively, which are preferably formed at draining angles in the head of the cylinder to enable liquid fuel and oil to drain off into the cylinder.

Plug 6 is preferably any suitable type of "cold" plug selected for its rapid heat dissipating properties. The particular plug 6 shown in Figs. 1 and 2 is a B. G. Hornet No. 4 having a small mica insulator 10, although this particular plug is shown simply for purposes of illustration as any other plug having good heat dissipating properties may be used equally well. Plug 6 has its spark gap extending well into the combustion chamber of the cylinder head and is preferably

pointed toward the center of the combustion space so that ignition from this plug will spread instantly throughout the entire compressed charge.

5 Priming plug 7 is preferably selected for its good insulating properties, the particular plug 1 shown in Figs. 1 and 2 being a Robert Bosch midget 12 mm. plug having a so-called petticoat porcelain insulator 12 which is a good high tension insulator. Recess 9 containing plug 7 is preferably set at such an angle that its entrance is adjacent the water jacketed wall 2 of the cylinder, this being the region of the combustion chamber where the radiant heat is at a minimum.

10 Plugs 6 and 7 may be connected in series or in parallel and may be functioned by any suitable source of timed interrupted current such as a dual ignition magneto or a battery controlled by 15 a suitable distributor or breaker. In the system of Fig. 2, wherein the two plugs are permanently connected in circuit with the energizing current, induction coil 13 has its primary winding connected to any suitable source of timed interrupted 20 current and has a secondary winding 14 which is preferably grounded at its midpoint. Winding 14 has one end connected to plug 6 and the other end connected to plug 7. Grounding of 25 secondary winding 14 at its midpoint reduces the danger of failure of ignition since, if one plug fails due to any cause such as its terminal connector becoming detached, the other plug will 30 continue to operate as before.

The operating characteristics of plugs 6 and 7 35 are illustrated graphically in Fig. 3 wherein the ordinates represent electrical ignition efficiency in terms of percentage and the abscissae represent temperature in degrees Fahrenheit. Under starting conditions and idling and low speeds, 40 priming plug 7 functions at 100% of its electrical ignition efficiency, having sufficient insulating surface to prevent fouling. When the temperature rises above about 250° F. the electrical ignition efficiency of plug 7 diminished due to the 45 presence of a short-circuiting element of gas generated in the zone of the spark gap. Around 500° F. the electrical ignition efficiency of plug 7 drops sharply until at 750° F. it has only about 50% of its original potential in the center of hotness of its spark. An ordinary four-cycle engine 50 of the type shown in Fig. 1 will develop a maximum temperature of around 2000° F. at which plug 7 may be completely short-circuited.

55 At the time the electrical ignition efficiency of plug 7 begins to fall the increasing temperature will have cleaned plug 6 of any surface condensation which has caused leakage and short-circuiting of the high tension current in this plug. As this deposit burns off, starting around 250° F., the electrical ignition efficiency of plug 6 rises 60 sharply, and when the deposit is completely burned off plug 6 will function as the main ignition point at 100% of its electrical ignition efficiency. The dotted line in Fig. 3 is a composite 65 curve representing the combined ignition characteristics of plugs 6 and 7. Up to about 250° F. this curve is coincident with the curve of plug 7 which is operating at 100% of its efficiency. At 70 that point the efficiency of plug 7 drops slightly while that of plug 6 rises sharply, the combined efficiency of the plugs being about 180% at 500° F. as shown by the dotted curve. At 750° F. the combined efficiency of the plugs is about 150% and above that temperature the efficiency decreases rapidly, dropping to 100% when plug 7

is completely short circuited. When the combustion chamber cools due to continued idling or operating at low speeds the action of the plugs is reversed but the combined efficiency of the plugs never drops below the maximum or 100% efficiency of either plug alone.

5 The ignition system of Fig. 4 is similar to that shown in Fig. 2 except that spark plugs 15 and 16 are two of the series made by the Champion Spark Plug Co., cold plug 15 being the Champion R-7 and priming plug 16 being the Champion #7. Plug 15 has a small insulating surface 17 and metal gaskets 18, 19, and 20 contacting with the metal shank whereby the radiant heat impinging on the plug is rapidly dissipated. Plug 15 10 16 has an elongated porcelain insulator 21 sufficient to prevent fouling by deposited carbonaceous material. These plugs have the same general characteristics illustrated in Fig. 3.

The vertical two-cycle engine shown in Fig. 5 20 is of the usual construction having a cylinder 23 which may be water-jacketed or provided with air-cooled fins 24, crank case 25 and explosion driven member or piston 26 connected to crank shaft 27 by connecting rod 28. The engine is 25 also provided with valved inlet 29, transfer port 30 and exhaust port 31. The cylinder head is provided with recesses 32 and 33 for the reception of spark plugs 34 and 35 both of which are adjacent the air-cooled cylinder wall.

30 Plug 34 may be any suitable type of cold plug, that shown in Figs. 5 and 6 being a Champion R-2 having a small insulating surface 36 and metal gaskets 37 and 38 contacting with the metal shank. Plug 35 may be any suitable type 35 of priming plug and in the form here shown is a Champion 14 m. m. special plug having an elongated porcelain insulator 39 and an outer metal jacket or bushing 40 which surrounds the spark gap, forming a recess or pocket 41 having 40 a restricted orifice or passage 42. This passage is disposed at such an angle to recess 41 that the wall of the passage absorbs the radiant heat of combustion which enters the passage and thereby prevents such heat from directly impinging 45 on and overheating plug 35 which in some engines would become excessively hot if mounted in a more exposed position. Bushing 40 is made of heat absorbing materials such as iron or steel and hence the wall of passage 42 does not reflect 50 heat especially since said wall is usually coated with carbon. Bushing 40 may be of any suitable diameter, for example it may have a $\frac{1}{8}$ " S. A. E. thread adaptable to various four-cycle automobile engines as well as to the two-cycle engine of 55 Fig. 5. This bushing may be furnished as a part of the plug or may be formed integral with or secured to the cylinder head. An advantage of making the bushing a part of the cylinder head, and using different sized plugs, is that it becomes 60 impossible to insert the plugs in the wrong positions. In the example given above plug 34 is 18 m. m. in diameter, which is considerably larger than plug 35.

65 On the compression stroke piston 26 forces a small amount of the fuel charge through passage 42 into recess 41. Passage 42 is narrow enough to develop mechanical heat of friction in the charge passing through it and since the spark gap of plug 35 is in close proximity to passage 42 the 70 mechanical heat of friction will gasify a portion of the charge in the zone of the spark gap where the charge will be ignited before such heat has been dissipated to any large extent.

75 Scavenging of recess 41 is accomplished auto-

5 matically due to the position of the spark gap of
 plug 35 in said recess. After each explosion the
 pressure in recess 41 drops to the same point as
 the pressure in the cylinder and most of the
 10 exhaust gas flows out of said recess. On the
 following compression stroke the compressed fresh
 mixture forces the residual exhaust gas in recess
 41 back to the base of the plug. The points of
 15 the spark gap are close enough to passage 42,
 and the clearance back of the points is sufficient
 to allow such residual exhaust gas to be pushed
 20 back away from the points on each compression
 stroke.

15 Although no one spark plug has yet been de-
 signed to combine the advantages of good elec-
 trical insulation and good heat dissipation, these
 20 advantages are effectively combined in the two
 or more plugs described above. I do not limit
 myself to two spark plugs in a cylinder, as I may
 25 employ a plurality of cold plugs and a plurality
 of priming plugs in one cylinder, or in some cases
 may use a single plug of one type and a plurality
 30 of plugs of another type in one cylinder con-
 nected either in series or in parallel and operated
 in any suitable manner. Many variations in the
 arrangement and mode of operation of the spark
 35 plugs and the ignition system as a whole will
 readily occur to those skilled in the art without
 departing from the scope and spirit of the ap-
 pended claims.

30 The invention claimed is:

1. Method of maintaining uniform combustion
 35 of a compressed mixture in the combustion space
 of a combustion engine which comprises subject-
 ing successive charges of said mixture to a plu-
 rality of timed interrupted sparks which vary
 40 oppositely in intensity with variations in tem-
 perature within said combustion space.

2. Method of maintaining uniform combustion
 45 of a compressed mixture in the combustion space
 of a combustion engine which comprises subject-
 ing successive charges of said mixture to a plu-
 rality of timed interrupted sparks varying oppo-
 sitely in intensity with variations in temperature
 50 within said combustion space and having at all
 times a combined intensity at least equal to the
 maximum intensity of either of said sparks alone.

3. Method of maintaining uniform combustion
 55 of a compressed mixture in the combustion space
 of a combustion engine which comprises subject-
 ing successive charges of said mixture to a timed
 interrupted spark having a maximum intensity
 60 at relatively low temperatures within said com-
 bustion space and simultaneously subjecting each
 charge of said mixture to a timed interrupted
 spark having a maximum intensity at relatively
 65 high temperatures within said combustion space.

4. An ignition system for combustion engines
 70 comprising a spark plug having high electrical
 ignition efficiency when subjected to relatively low
 temperatures and low electrical ignition efficiency
 when subjected to relatively high temperatures
 75 within the combustion space, and a second spark
 plug in circuit therewith having high electrical
 ignition efficiency when subjected to relatively
 high temperatures and low electrical ignition effi-
 ciency when subjected to relatively low tempera-
 80 tures within the combustion space.

5. An ignition system for combustion engines
 85 comprising a spark plug having maximum elec-
 trical ignition efficiency when subjected to rela-
 tively low temperatures within the combustion
 space, and a second spark plug in circuit with
 90 said first plug having maximum electrical igni-
 tion efficiency when subjected to relatively high
 temperatures within said combustion space.

9. An ignition system for combustion engines comprising a spark plug having high insulating properties and maximum electrical ignition efficiency when subjected to relatively low temperatures within the combustion space, a second spark plug having rapid heat dissipating properties and maximum electrical ignition efficiency when subjected to relatively high temperatures within said combustion space, and means for simultaneously energizing said spark plugs.

10. An ignition system for combustion engines comprising a spark plug having high insulating properties and maximum electrical ignition efficiency when subjected to relatively low temperatures within the combustion space, a second spark plug having rapid heat dissipating properties and maximum electrical ignition efficiency when subjected to relatively high temperatures within said combustion space, and means for simultaneously energizing said spark plugs.

15. An ignition system for combustion engines comprising a spark plug having high insulating properties and maximum electrical ignition efficiency when subjected to relatively low temperatures within the combustion space, a second spark plug having rapid heat dissipating properties and maximum electrical ignition efficiency when subjected to relatively high temperatures within said combustion space, and means for simultaneously energizing said spark plugs, said spark plugs having at all of said temperatures a combined electrical ignition efficiency at least equal to the maximum electrical ignition efficiency of either spark plug alone.

20. An ignition system for combustion engines comprising a pair of spark plugs having individual electrical ignition characteristics which vary over the range of temperatures developed in the combustion space of the engine at varying engine speeds, one of said spark plugs having a maximum electrical ignition efficiency in the lower portion of said temperature range, the other of said spark plugs having a maximum electrical ignition efficiency in the upper portion of said temperature range, and said spark plugs together having a combined electrical ignition characteristic over the entire temperature range at least equal to the maximum electrical ignition efficiency of either spark plug alone.

25. An ignition system for combustion engines comprising a pair of spark plugs having individual electrical ignition characteristics which vary over the range of temperatures developed in the combustion space of the engine at varying engine speeds, one of said spark plugs having an electrical ignition efficiency attaining a maximum in the lower portion of said temperature range and dropping sharply in the upper portion of said temperature range, and the other of said spark plugs having low electrical ignition efficiency in the lower portion of said temperature range and high electrical ignition efficiency in the upper portion of said temperature range, and means for simultaneously energizing said spark plugs.

30. An ignition system for combustion engines comprising a pair of spark plugs having individual electrical ignition characteristics which vary over the range of temperatures developed in the combustion space of the engine at varying engine speeds, one of said spark plugs having an electrical ignition efficiency attaining a maximum in the lower portion of said temperature range and dropping sharply in the upper portion of said temperature range, and the other of said spark plugs having an electrical ignition efficiency at a minimum in the lower portion of said temperature range and increasing sharply at the point where the electrical ignition efficiency of the first mentioned spark plug begins to drop, and a source of energizing current permanently connected to both of said spark plugs.

35. An ignition system for combustion engines comprising a spark plug having sufficient insu-

- lation adjacent its spark gap to prevent fouling at the relatively low temperatures developed in the combustion space of the engine when the engine is started and operated at low speeds, a second spark plug having rapid heat dissipating properties and high electrical ignition efficiency at the relatively high temperatures developed in said combustion space when the engine is operated at high speeds, and means for simultaneously energizing said spark plugs.
12. A combustion engine comprising a combustion space having a recess for a spark plug, a spark plug having relatively high insulating properties and relatively low heat dissipating properties mounted in said recess, a restricted passage permanently connecting said recess with said combustion space to minimize radiation of heat to said spark plug, and a second spark plug adapted for rapid heat dissipation having its spark gap extending into said combustion space.
13. A combustion engine comprising a combustion space, a spark plug having a high tension insulator in constant communication with said combustion space, means for shielding said spark plug from the radiant heat of combustion, and a second spark plug having a rapid heat dissipating insulator and a spark gap mounted in exposed position in said combustion space.
14. A combustion engine comprising a combustion space and a plurality of spark plugs connected with said combustion space and adapted to spark simultaneously, one of said spark plugs having a high tension insulator and a spark gap shielded from the radiant heat in said combustion space, and another of said spark plugs having a rapid heat dissipating insulator and a spark gap mounted in exposed position in said combustion space.
15. A combustion engine comprising a combustion space having an outer cooling surface and a plurality of spark plugs set at draining angles communicating with said combustion space and adapted to spark simultaneously, one of said spark plugs having relatively high insulating properties and relatively low heat dissipating properties and having a spark gap shielded from said combustion space adjacent said cooling surface, and another of said spark plugs having relatively high heat dissipating properties and relatively low insulating properties and having a spark gap mounted in exposed position in said combustion space.
16. An ignition system for combustion engines comprising a spark plug having relatively high insulating properties and relatively low heat dissipating properties and a second spark plug in circuit therewith having rapid heat dissipating properties and relatively low insulating properties, and means for energizing said spark plugs.
17. An ignition system for combustion engines comprising a spark plug having relatively high insulating properties and relatively low heat dissipating properties and a second spark plug hav-
- ing rapid heat dissipating properties and relatively low insulating properties, and means for simultaneously energizing said spark plugs.
18. An ignition system for combustion engines comprising a spark plug having relatively high insulating properties and relatively low heat dissipating properties and a second spark plug having rapid heat dissipating properties, a source of interrupted current, and an induction coil having a primary winding connected to said source of current and a secondary winding connected to said spark plugs.
19. A combustion engine comprising a combustion space, a spark plug having relatively high insulating properties and relatively low heat dissipating properties communicating with said combustion space, means for heating a portion of the compressed charge adjacent said spark plug, and a second spark plug adapted for rapid heat dissipation having its spark gap extending into said combustion space.
20. A combustion engine comprising a combustion space containing a recess, a spark plug having relatively high insulating properties and relatively low heat dissipating properties mounted in said recess, a passage connecting said recess with said combustion space, said passage being narrow enough to develop mechanical heat of friction in the compressed charge passing through said passage into said recess, and a second spark plug adapted for rapid heat dissipation having its spark gap extending into said combustion space.
21. A combustion engine comprising a combustion space containing a recess for a spark plug, a passage connecting said recess with said combustion space, a spark plug having relatively high insulating properties and relatively low heat dissipating properties mounted in said recess and having a spark gap adjacent said passage, said passage being narrow enough to develop mechanical heat of friction in the compressed charge passing through said passage into said recess whereby to gasify the charge adjacent said spark gap, and a second spark plug adapted for rapid heat dissipation having its spark gap extending into said combustion space.
22. A cylinder head for a combustion engine containing a recess for the reception of a spark plug having high tension insulating properties and a recess of different size for the reception of a spark plug having rapid heat dissipating properties.
23. A cylinder head for a combustion engine containing a plurality of recesses of different sizes for the reception of spark plugs of different sizes, one of said recesses extending directly into the combustion side of said cylinder head and another of said recesses being shielded from the combustion side of said cylinder head and having a restricted passage connected thereto.

WILLIAM HARPER, JR.
